UNITED STATES PATENT OFFICE

JAMES M. DODDRIDGE, OF MILTON, INDIANA

HIGHWAY GUARD

Application filed November 29, 1929. Serial No. 410,298.

This invention relates to a protective fence, particularly for use along dangerous sections of highway.

One object of the invention is to provide a fence which can be economically built from standard steel sections such as I-beams, channels and angle irons and which is easily adjustable to curves and gradients.

One feature of the invention consists in novel means for anchoring the upright posts for forming the support members of the fence.

Another feature resides in a novel means of fastening channel section guard rails to the said posts.

Other objects and features of the invention will be fully understood from the accompanying drawings and the following description and claims:

Fig. 1 is an elevational view of a section of the fence showing the upright supports and guard rails. Fig. 2 is an elevational view in section illustrating one of the said upright supports with its anchoring means and guard rail connections. Fig. 3 is substantially a plan view taken on the line 3-3 of Fig. 2 and illustrating the said anchoring means in detail. Fig. 4 illustrates an alternative method of fastening the channel guard rails to the upright supports. Fig. 5 is a plan view of the arrangement of parts at the top of said posts.

A plurality of upright posts 10, herein shown as standard I-beam sections, are provided. Each of the posts is preferably set in a concrete base 11. For anchoring the posts against the shock of collision with a vehicle, a reinforcing member 12 is provided. The said member 12 is formed substantially U-shaped with outwardly bent extremities 13. The base portion 14 of the member 12 engages the upright post 10 at a position at or near the ground line. The outwardly-turned extremities 13 are embedded in an anchorage 15 of concrete or a similar material. The remainder of the member 12 is preferably also embedded in concrete 16. By this construction, an extremely simple, inexpensive and effective reinforcement is obtained for the upright posts.

The fence is preferably formed with a lower guard rail 17 and an upper guard rail 18. The lower guard rail 17 is formed of a channel member which may be cut in sections extending from post to post or in longer sections, depending upon the nature of the highway grade. The channel member 17 is turned with its flanges 19 toward the post and its web portion 20 toward the highway. Thus a flat surface free from obstructions is presented toward the highway. For fastening the channel member 17 to the posts 10, a plurality of L-head bolts 21 are provided having their heads 22 upwardly turned and engaging holes 23 in the flanges of the channel. Four of the bolts 21 are provided for each post, two on each side of the post, one of which engages the upper flange and the other the lower flange of the channel 17.

Plates 32 are provided adjacent the highway side of each post and plates 24 adjacent the rearward side. Each of the bolts 21 passes through holes in the said plates and a nut 25 threadedly engages the rearward end of each bolt. When the nuts 25 are tightened into position, the plates 24 are clamped against the rearward side of the post and the guard rail 17 is clamped against the plates 32 which are in turn clamped against the highway side of the post. By varying the thickness of the plates 32, the web of the guard rail may be positioned any desired distance from the post. It is important that the guard rail be positioned far enough from the post so that no overhanging portion of a vehicle, such as a fender, can strike the post. Where channels are used having flanges sufficiently deep to accomplish this purpose, the plates 32 may be omitted and the channel clamped directly to the post. By this construction, it is possible to readily adjust the position of the guard rail 17 upon the post 10. No special parts, such as castings or specially rolled shapes, are required, and none of the fastening members project beyond the surface of the web 20 of the guard rail.

In Fig. 4 is illustrated an alternative form of fastening for the channel member 17.

Therein a plurality of L-head bolts 121 are supplied threaded over substantially their entire length. A pair of plates 124 similar to the plates 24 is provided for each pair of bolts, one pair of plates being positioned adjacent one surface of the post 10 and the other pair of plates adjacent the opposite surface. Nuts 125 threadedly engage the bolts 121 and serve to clamp the said plates against the vertical member. With this construction, the up-turned ends 122 of the bolts 12 serve simply as hooks upon which to hang the channel member 17 which is then easily removable without altering the position of the bolts or nuts, or may be attached permanently by using a nut on the upturned portion of the bolt after it has passed through the flange of the channel.

The upper guard rail 18 is herein shown in the form of an angle iron which may be cut to lengths to extend from post to post or may be cut to longer lengths, depending upon the highway grade. At the top of each post 10 a slotted hole 26 is cut in the web. A U-bolt 27 is positioned in the said hole and a plate 28 having slotted holes 29 is placed at the top of the column with the ends of the U-bolt extending through the said holes. The guard rail 18 is then positioned with one leg resting upon the plate and with the end of the U-bolt projecting through slotted holes therein. Nuts 31 are applied to the ends of the U-bolts and serve to clamp the guard rail 18 and plate 28 to the column 10. In this construction, the plate 28 serves as a seat for the guard rail 18. This is particularly important at those posts where the guard rail 18 is formed with a joint as in Fig. 5. The holes 29 and 30 are of slotted form for the purpose of adjusting slight inaccuracies in the positioning of the posts. The provision of slotted holes in the plate 28 as well as in the guard rail 18 allows the plate 28 to be positioned to give an adequate support to the abutting ends of two adjacent guard rail members 18, even though the said ends do not abut at the exact center line of the column 10. This feature is clearly shown in Fig. 5 wherein the right-hand member 18 would have practically no bearing upon the column 10 if the plate 28 were not used and would have a relatively small bearing on the plate 28 if the holes 29 were not of slotted form.

It is to be understood that variations in the details of construction herein shown may be made without departing from the spirit of the invention. For example, it is not necessary that the upright columns be of I-beam section. Tubular columns or other standard shapes may be used as well and the features of the invention hereinbefore described are equally applicable.

65 The invention claimed is:

1. In a protective fence for highways the

combination of an upright supporting post having a hole therethrough adjacent its upper end, a plate for the top of said post, an angle iron guard rail having one leg resting upon said plate and a bolt passing through the said hole in said post for fastening said guard rail and plate to said post.

2. In a protective fence for highways the combination of an upright supporting post having a hole therethrough adjacent its upper end, a plate for the top of said post, an angle iron guard rail having one leg resting upon said plate and a U-bolt passing through the said hole in said post for fastening said guard rail and plate to said post.

3. In a protective fence for highways the combination of an upright supporting post having a hole therethrough adjacent its upper end, a plate for the top of said post having an elongated hole therein, a guard rail resting upon said plate and having a hole therein and a bolt engaging all of said holes for fastening said guard rail and plate to said post.

4. In a protective fence for highways, the combination of a plurality of upright supporting posts, a guard rail formed of a channel shaped section having its flanges toward said posts and its web portion toward the highway, a plurality of bolts having L-shaped heads engaging holes in a flange of said guard rail, and means for supporting said bolts upon said posts.

5. In a protective fence for highways the combination of a plurality of upright supporting posts, a guard rail formed of a channel shaped section having its flanges toward said posts and its web portion toward the highway, a perforated plate engaging the side of each post opposite said guard rail, a bolt on each side of each post, said bolts each having a threaded end extending through a perforation in said plate and an L-shaped head engaging a hole in a flange of said guard rail, and a nut engaging the threaded end of each of said bolts for adjustably clamping said guard rail and plates to said posts.

6. In a protective fence for highways the combination of a plurality of upright supporting posts, a guard rail formed of a channel shaped section having its flanges toward said posts and its web portion toward the highway, a plurality of bolts arranged two on each side of each post, said bolts having L-shaped heads engaging holes in the flanges of said channel member, one bolt on each side of each post engaging the upper flange and one the lower flange, plates engaging the side of each post opposite to said guard rail, said plates having holes engaging the ends of said bolts and nuts threadedly engaging said bolt ends for adjustably clamping said plate and said guard rail to said posts.

7. In a protective fence for highways the combination of a plurality of upright sup-

porting posts, a guard rail formed of a channel shaped section having its flanges toward said posts and its web portion toward the highway, spacer plates interposed between 5 said flanges and said posts, a perforated plate engaging the opposite side of each post, a bolt on each side of each post, said bolts each having a threaded end extending through a perforation in one of said perforated plates 10 and an L-shaped head engaging a hole in a flange of said guard rail, and a nut engaging the threaded end of each of said bolts for adjustably clamping said guard rail and plates to said posts.

15 8. In a protective fence for highways the combination of a plurality of upright supporting posts, a guard rail formed of a channel shaped section having its flanges toward said posts and its web portion toward the 20 highway, spacer plates interposed between each flange and said posts, a plurality of bolts arranged two on each side of each post, said bolts having L-shaped heads engaging holes in the flanges of said channel member, 25 one bolt on each side of each post engaging the upper flange and one the lower flange, perforated plates engaging the side of each post opposite to said guard rail, said plates having holes engaging the ends of said bolts 30 and nuts threadedly engaging said bolt ends for adjustably clamping said plates and said guard rail to said posts.

In witness whereof, I have hereunto affixed
my signature.
